US0D1091525S

(12) **United States Design Patent** (10) Patent No.: **US D1,091,525 S**
(45) Date of Patent: ** Sep. 2, 2025

(54) **MOBILE PHONE STAND**

(71) Applicant: **Hui Tang**, Sichuan (CN)

(72) Inventor: **Hui Tang**, Sichuan (CN)

(**) Term: **15 Years**

(21) Appl. No.: **29/915,826**

(22) Filed: **Nov. 3, 2023**

(51) LOC (15) Cl. **14-03**

(52) U.S. Cl.

USPC **D14/253**

(58) **Field of Classification Search**

(57) **CLAIM**

The ornamental design for a mobile phone stand, as shown and described.

DESCRIPTION

FIG. 1 is a front elevation view of a mobile phone stand showing the new design;

FIG. 2 is a back elevation view thereof;

FIG. 3 is a left-side view thereof;

FIG. 4 is a right-side view thereof;

FIG. 5 is a top plan view thereof;

FIG. 6 is a bottom plan view thereof;

FIG. 7 is a perspective view thereof; and,

FIG. 8 is another perspective view thereof.

1 Claim, 8 Drawing Sheets
